CLAIM

The ornamental design for a tubular tin purse, as shown and described.

DESCRIPTION

FIG. 1 is a front perspective view of a tubular tin purse showing our new design;

FIG. 2 is a top plan view thereof;

FIG. 3 is a front elevational view thereof;

FIG. 4 is left side elevational view, the right side being a mirror image thereof;

FIG. 5 is a bottom plan view thereof; and,

FIG. 6 is a rear elevational view thereof.

The broken line showing of a handle, in FIGS. 1–4, and of a clasp, in FIGS. 1–4, is for illustrative purposes only and forms no part of the claimed design.
